UNITED STATES PATENT OFFICE.

JOHN W. MARK, OF NEW YORK, N. Y.

DESIGN FOR A LIGHT OR TILE.

SPECIFICATION forming part of Design No. 27,761, dated October 19, 1897.

Application filed September 8, 1897. Serial No. 650,991. Term of patent 14 years.

To all whom it may concern:

Be it known that I, JOHN W. MARK, of New York, in the county of New York, and in the State of New York, have invented a certain new and original Design for a Light or Tile; and I do hereby declare that the following is a full, clear, and exact description thereof, reference being had to the accompanying drawings, in which—
Figure 1 is a perspective view of a light or tile embodying my design, and Fig. 2 a plan view thereof.
Letters of like name and kind refer to like parts in each of the figures.
The object of my invention is to provide a new shape or configuration for lights or tiles; and to this end said invention consists in the design for a light or tile, substantially as herein set forth.
The essential feature of my design consists of a light or tile A, that is quadrangular or four-sided, with a depression B in the central portion of each side.
The depression B slopes or inclines from

one face of the tile, disappearing when the opposite face is reached, and the surface b at each end thereof is an inclined one.

Each corner of the light or tile A is chamfered or beveled off, the surface thereof being inclined from one face of the light or tile to the other, as in the case of the depressions B and B. Thus while one face of the light or tile shows the shape of a quadrangle with a depression in each of its four sides and its corners beveled the other face presents such a shape with unbroken sides.

Having thus described my invention, what I claim is—

The design for a light or tile, substantially as herein set forth.

In testimony that I claim the foregoing I have hereunto set my hand this 1st day of September, 1897.

JOHN W. MARK.
